UNITED STATES PATENT AND TRADEMARK OFFICE
CERTIFICATE OF CORRECTION

PATENT NO. : Des. 567,476 S
APPLICATION NO. : 29/244834
DATED : April 29, 2008
INVENTOR(S) : Harland

Page 1 of 3

It is certified that error appears in the above-identified patent and that said Letters Patent is hereby corrected as shown below:

The title page, showing an illustrative figure, should be deleted and substitute therefor the attached title page.

Delete drawing sheet 1 and substitute therefor the drawing sheet, consisting of figures 1-3 as shown on the attached pages.

Signed and Sealed this

Thirtieth Day of November, 2010

David J. Kappos
Director of the United States Patent and Trademark Office
